Specification for Design.

Patented Mar. 15, 1921.

Application filed September 17, 1920. Serial No. 410,990. Term of patent 7 years.

To all whom it may concern:

Be it known that I, JACOB BERENZWEIG, a citizen of the United States, residing at Los Angeles, in the county of Los Angeles and State of California, have invented a new, original, and ornamental Design for a Garden-Apron, of which the following is a specification, reference being had to the accompanying drawing, forming a part thereof, the same being a view of the front of a garden-apron, showing the design.

I claim:

The ornamental design for a garden apron, substantially as shown.

Signed at Los Angeles, in the county of Los Angeles, and State of California, this 11th day of September, 1920.

JACOB BERENZWEIG.
